UNITED STATES PATENT OFFICE.

CLIFFORD C. MOSHER, OF LIMA, OHIO.

ADJUSTABLE BLADE FOR MIXING MACHINES.

Application filed May 14, 1923. Serial No. 638,607.

To all whom it may concern:

Be it known that I, CLIFFORD C. MOSHER, a citizen of the United States, residing at Lima, in the county of Allen and State of Ohio, have invented new and useful Improvements in Adjustable Blades for Mixing Machines, of which the following is a specification.

This invention relates to mixing machines 10 of general application, for example to rubber mixers, dough mixers, concrete and asphalt mixers and similar machines, and consists in an improved form of adjustable blade for use in such machines.

15 In machines of the kind to which the present invention is applicable, the blades are set at an angle to the axis of the shaft so as to exert longitudinal impelling action on the material, either to feed it towards one end of the drum or from both ends towards the center of the same, some machines being what is known as of the "end-dump" type, and others as of the "center bottom-dump" type. The blades are set staggered on the 25 shafts so as to act like a screw conveyer. It is also desirable to be able to adjust the blades radially of the shafts to take up wear and to be able to reduce or increase the space between the ends of the blades and the inside surface of the drum.

30 By the improved construction which I have devised and will now describe in detail, the blades can be set so as to constitute in effect either a right-hand or a left-hand screw, and can also be adjusted radially.

In the accompanying drawings, I have 35 illustrated my invention as applied to a machine having two parallel blade-carrying shafts, geared together and passing through a drum having a double semi-circular bottom, but, as will be obvious, it is equally applicable to a machine having but one shaft and a single semi-circular bottom.

In the drawings,

40 Fig. 1 is an end elevation, one half in vertical section through the drum, of a mixer equipped with the improved blades;

Fig. 2 is a plan view of one of the blades complete;

45 Fig. 3 is an end view of one of the blade-holding arms;

Fig. 4 is a perspective view of one of the blades complete;

50 Fig. 5 is a similar view looking from the other side;

Fig. 6 is a perspective view of the blade-holding arm, and

Fig. 7 is a perspective view of the blade proper detached from the arm.

The machine illustrated in these views 50 comprises a drum 1, with double semi-circular bottom to conform to the circles of revolution of the blades and two parallel rotary shafts 2, 2, which carry the blades, these shafts being square in cross-section 65 within the drum, as shown at the right in Fig. 1. 4 represents one of the driving gears, and it will be understood, without further description or illustration, that the shafts are geared together so as to rotate in 70 opposite directions, as is well known in the art and that it is immaterial to my present invention whether the machine has two shafts or only one.

Each mixing blade consists of a blade-holding arm 5, the hub 6 of which is so notched at 8 as to fit on the corners of the square shaft in any one of eight positions around the same, and it is held there by bolts 9 passed through the holes 10. The 80 blade holding arm extends radially from the hub 6 and resembles an angle-iron in form with two plane surfaces 7, 7, at right angles to each other and provided with slots 11, 11, for the bolts 12, 12, by which 85 the blades proper 13, are secured. Each blade has four bolt-holes 15 for the reception of said bolts 12, two of said holes being used when the blade is secured to one of the faces 7 and the other two holes being used 90 when the blade is secured to the other face 7 of the arm 5. Each face 7 is further provided with a plurality of parallel transverse notches 16, with which a triangular projection 17 on the blades 13 cooperates to hold 95 the latter against slipping, while permitting a radial adjustment of the blades, the slots 11 enabling the position of the blade-securing bolts 12 to be varied to take care of said adjustment.

100 The exact shape of the blade-holding arms illustrated is not essential to the inventive idea, as expressed in the claims, but may be varied to suit the circumstances.

Having thus described my invention, 105 what I claim is:

1. An adjustable blade for mixing machines, comprising a blade-holding arm adapted to be clamped on a shaft and having two radial plane faces at right angles 110

to each other, and a blade adapted to be secured to either of said faces so as to act with either a right or left hand screw action on the material.

- 5 2. Adjustable blades for mixing machines, comprising arms, the hubs of which are notched to fit the corners of a square shaft, and are provided with bolt holes whereby they can be clamped on said shaft,
10 said arms having faces at right angles to each other with slots and transverse grooves, and blade members provided with bolt holes and a transverse rib, whereby said blade members can be secured to either of said faces, so as to set right or left, and can be
15 radially adjusted on said arms.
3. A mixing machine comprising a drum, a square shaft passing through the same, arms provided with half hubs fitting said
20 shaft in any one of eight staggered positions around the same, each arm having two

radial surfaces lying in planes at right angles to each other and at 45° to the axis of the shaft, blades securable to either of said faces, and means whereby said blades can be adjusted radially on said faces.

4. A mixing machine, comprising a drum and a pair of parallel shafts passing therethrough and geared to rotate in opposite directions, said shafts having a polygonal cross section within said drum, blade-supporting members and means to clamp them on said shafts in relatively staggered positions around the same, each of said members having radial plane surfaces set at
30 right angles to each other, and mixing blades adapted to be secured to either of said surfaces.

In testimony whereof I have hereunto set my hand.

CLIFFORD C. MOSHER.
